CATHODE RAY APPARATUS

William J. Morlock, Collingswood, N. J., assignor
to Radio Corporation of America, New York,
N. Y., a corporation of Delaware

Application November 30, 1932, Serial No. 644,931

2 Claims. (Cl. 250—27.5)

My invention relates to improvements in cathode ray apparatus and the method of operating the same.

In some television systems, a cathode ray tube is utilized at the transmitting station to develop picture signals for transmission, and a cathode ray tube is utilized at the receiving station to reproduce an image of the transmitted picture, under control of the picture signals as received. 5
10 The transmitting and receiving tubes are similar to the extent that each tube is provided with screen structure and with means in the form of an electron gun for developing a cathode ray and for directing the same at the screen structure. 15
15 Means in the form of electromagnetic coils or electrostatic plates are employed to deflect the ray in different directions so that the same is caused to scan the screen structure over a definite pattern, usually a square or rectangular portion 20 of the screen structure.

In making these tubes, it is attempted to make the axis of the electron gun exactly in line and coincident with the axis of the tube, so that the undeflected ray is directed exactly at the center 25 of the screen structure. When this condition is obtained, the center of the pattern over which the ray scans the screen structure is exactly at the center of the latter. In this connection, however, the construction is not always perfect as 30 regards the lining-up of the electron gun. The result is that the undeflected ray is directed to a spot on the screen structure substantially removed from the center thereof. When the ray is deflected, therefore, the center of the area 35 scanned is off to one side a substantial amount, and in some cases the discrepancy is so great that the ray scans the side wall of the tube along one or more edges of the pattern.

With the foregoing in mind, it is one of the 40 objects of my invention to provide improved cathode ray apparatus and an improved method of operating the same whereby the cathode ray can be caused to scan the screen structure over a pattern whose center is coincident with the center of the screen structure, regardless of any 45 faulty construction whereby the axis of the electron gun is out of line with the axis of the tube.

Other objects and advantages will hereinafter 50 appear.
55 In accordance with my invention, a fixed auxiliary field is developed which is independent of the ray-deflecting field and is substantially symmetrical with respect to the undeflected ray, and the field is so adjusted that the undeflected ray is centered or brought back to the position where-

at it is directed exactly at the center of the screen structure.

Further, in accordance with my invention, it is proposed to utilize electromagnetic coils for deflecting the ray in at least one direction, and to supply to these coils a direct current of the proper strength and polarity for the purpose of directing the undeflected ray to the center of the screen structure. 5

My invention resides in the apparatus and the 10 method of operation of the character hereinafter described and claimed.

For the purpose of illustrating my invention, an embodiment thereof is shown in the drawing, wherein 15

Figure 1 is a perspective view, partly diagrammatic, of cathode ray apparatus embodying my invention; and

Figs. 2, 3 and 4 are diagrammatic views illustrative of several modifications. 20

In Fig. 1, the reference numeral 10 designates a cathode ray tube of the usual type employed at a television receiving station for reproducing an image of the transmitted object. This tube is provided, at one end thereof, with fluorescent screen 25 structure 12, and at its other end with a suitable electron gun 14 for developing a cathode ray 16 and directing the ray at the screen structure.

For the purpose of causing the ray to scan the screen structure over a rectangular area or pattern 18, electromagnetic coils 20 are utilized to periodically deflect the ray horizontally and electromagnetic coils 22 are utilized to periodically deflect the ray vertically. 30

If, in the construction of the tube, the axis of 35 the gun 14 is unintentionally made slightly out of line with the axis of the tube, the undeflected ray will be directed at a spot on the screen structure substantially removed from the center 24.

The area actually scanned will then be shifted 40 substantially from the desired area 18. In one form of my invention, this condition is corrected for by winding a few turns of wire around the coils 20 to provide the auxiliary series-connected coils 26. Similarly, a few turns of wire are wound 45 around the coils 22 to provide the auxiliary series-connected coils 28.

In operation, the coils 20 and 22 are connected to suitable electrical circuits for causing current waves of the proper shapes and frequencies to 50 pass through these coils.

The auxiliary coils 26 and 28 are excited from a suitable source 30 of direct current, through connections 32 and 34 connected, as shown, to the outside ends of these coils. The degree of exci- 55

tation of the coils 26 and 28 is controlled, respectively, by rheostats 36 and 38, each of the latter having a relatively high resistance value. The connections to the auxiliary coils 26 and 28 are made to give the proper polarities so that, when current is caused to flow through these coils, the undeflected ray is deflected downwardly or upwardly, and/or to the right or the left, as might be required to direct the ray at the center spot 24 of the screen structure. The amount of such deflection of the ray is controlled by adjustment of the rheostats 36 and 38.

By the means just described, a fixed auxiliary magnetic field, independent of the ray-deflecting field, and substantially symmetrical to the undeflected ray, is developed, and the ray is caused to pass through this auxiliary field during the normal scanning action under the influence of the ray-deflecting coils 20 and 22.

20 In the embodiment of my invention just described, the auxiliary coils 26 and 28 may be wound on separate pole pieces if there is not sufficient room to accommodate them on the ray-deflecting coils 20 and 22.

25 In Fig. 2 is shown a modification wherein the ray-deflecting coils 20 and 22 also are utilized for centering the undeflected ray. In this case, alternating-current-supply connections 40 and 42 are provided for supplying to the coils 20 and 22, respectively, current waves of the proper shapes and frequencies to cause the ray 16 to scan the area or pattern 18. Direct-current-supply connections 32a and 34a, corresponding to the connections 32 and 34 in Fig. 1, are connected to the outside ends of the coils 20. For the purpose of preventing the alternating current from entering the direct current voltage supply, coils 44 and 46, each of relatively high impedance, are disposed in and form part of the connections 32a and 34a, 40 the A. C. connections 40 being connected between these impedance coils and the coils 20. A rheostat 48 is provided for controlling the amount of direct current component in the coils 20, and serves the same purpose as the rheostat 36 in 45 Fig. 1.

The connections to the coils 22 are the same as those of the coils 20, the rheostat 50 serving the same purpose as the rheostat 38 in Fig. 1.

50 In operation, the polarities of the direct current sources 30a and 30b are made such that the undeflected ray is deflected in the proper directions to direct the same at the center spot 24 of the screen structure, and the rheostats 48 and 50 are adjusted to control the amount of deflection.

55 In Fig. 3, the operation is the same as in Fig. 2, except that condensers 52 and 54 are disposed between the alternating-current-supply connections 40 and 42 and the direct-current-supply connections to prevent the alternating current generator from short-circuiting the direct current source.

Fig. 4 illustrates another embodiment of my

invention wherein the deflecting coils are used for centering the ray, as in Figs. 2 and 3. In this case, however, the direct-current supply is taken from a potentiometer 56 connected as shown between ground and the high potential end of a shunt feed reactor 58 connected in the plate circuit of an output tube 60 forming part of a deflecting circuit 62. This circuit, as is well known, operates to supply to the coils 20 a current wave of the proper form and frequency. The power supply end of the reactor 58 is at a higher direct current potential than the plate end thereof, so that current will flow through the deflecting coils in the correct direction to center the ray 16. The ground end of the coils 20 is connected to the 15 adjustable contact 64 of the potentiometer, and by adjusting this contact, direct current can be made to flow through the coils to the plate of the tube 60, or from this plate through the coils. The undeflected ray, therefore, can be deflected in 20 either direction, as might be required to direct the same at the center spot 24.

25 Since the potentiometer 56 might offer an undesirable impedance to the alternating deflecting currents, the ground end of the deflecting coils is connected to ground through a by-pass condenser 66.

The same connections shown in Fig. 4 can be used for the vertical deflecting coils 22. That is, the voltage drop across the shunt feed reactor 30 in the deflection circuit for these coils is utilized in the same manner to cause the centering current to pass through the coils 22.

Various other modifications, within the conception of those skilled in the art, might be made 35 without departing from the spirit of my invention or the scope of the claims.

I claim as my invention:

1. In combination, a cathode ray tube having screen structure and an electron gun for directing 40 a cathode ray toward said structure, a yoke member surrounding the tube intermediate the gun and the screen structure and lying in a plane substantially normal to the axis of the electron gun, the said member having four extensions of 45 magnetically permeable material directed inward toward the tube and spaced apart circumferentially thereof substantially ninety degrees, a plurality of coils, at least one coil on each extension, each coil being connected in series-aiding 50 relation to an opposite coil, terminal connections for supplying the coils with fluctuating currents for ray deflection purposes, and terminal connections for supplying the coils with unidirectional 55 current whereby the locus of the scanning pattern of the ray on the fluorescent screen may be adjusted.

2. The invention set forth in claim 1, characterized in that the yoke member is also magnetically permeable.

WILLIAM J. MORLOCK.
